UNITED STATES PATENT OFFICE

WILLIAM H. NUTT, OF BEVERLY, MASSACHUSETTS, ASSIGNOR TO UNITED SHOE MACHINERY CORPORATION, OF PATERSON, NEW JERSEY, A CORPORATION OF NEW JERSEY

MACHINE FOR SLOTTING HEELS

Original application filed February 5, 1929, Serial No. 337,696. Divided and this application filed July 30, 1931. Serial No. 554,011.

This invention relates to machines for operating upon heels of shoes and is exemplified with reference to a machine designed to form heel cover receiving slots in heels.

5 In United States Letters Patent No. 1,761,021 there is disclosed a heel having a Y-shaped slot constructed and arranged to receive both of the forward marginal portions of the side cover of a Louis heel and an 10 end portion of a short heel breast covering flap. The straight and curved portions of the slot may be formed in separate operations in a machine such as disclosed in application for United States Letters Patent Serial No. 15 337,696, filed February 5, 1929, in my name, of which the present application is a division.

It is an object of the present invention to provide a machine for effectively and quickly forming in the breast of a heel a curved cover 20 receiving slot such, for example, as the curved slot which constitutes a part of the compound slot disclosed in the above-mentioned patent. To this end and in accordance with 25 a feature of the invention, the illustrated machine comprises a cutter and heel supporting means constructed and arranged for relative movement to form in the breast of a heel a laterally curved heel cover receiving slot and is provided with mechanism for defining 30 the path of relative movement of the cutter and the heel-supporting means. As herein shown, a barrel saw constitutes the cutter for forming the laterally curved heel cover receiving slot and in order to support and 35 present the heel to the saw, the illustrated machine is provided with a carrier or slide mounted for movement toward and away from the saw. The slide is constructed and arranged to support a trough-shaped heel 40 holder which may be adjusted at a predetermined angle to the saw to control the angle at which the slot is disposed to the breast of the heel, the heel holder also being adjustable in a plane inclined to the axis of rotation of 45 the saw to form the curved slot at the desired location in the breast of the heel. The illustrated trough-shaped heel holder is so constructed that when the heel is placed therein, it will centralize itself with respect 50 to the holder so that the median line of the

breast of the heel, which projects beyond the holder, will lie in a vertical plane including the axis of rotation of the saw, the heel being clamped in position in the holder by engaging the top lift receiving and the attaching 55 faces of the heel. In order to vary the depth of the slot formed in the heel, movement of the slide toward the saw is preferably limited, provision being made to vary the extent of this movement according to the depth of 60 the slot desired.

The invention will be explained with reference to the accompanying drawings, in which

Fig. 1 is a perspective view of the illustrated machine for forming curved heel cover receiving slots in the breasts of heels and illustrating a semi-Louis heel positioned in the machine;

Fig. 2 is a side elevation of a portion of 70 the machine shown in Fig. 1 and showing a full Louis heel positioned in the machine;

Fig. 3 is an end view of the illustrated machine;

Fig. 4 illustrates a heel the breast of which 75 has been slotted to receive a side cover and a heel breast covering flap; and

Fig. 5 is a sectional view of the heel illustrated in Fig. 4 taken along the line V—V of Fig. 4.

In covering Louis heels having Y-shaped grooves such as disclosed in the above-mentioned United States Letters Patent No. 1,761,021, it is customary to inturn the forward marginal portions of the side cover of 85 each of the heels into the entire slot and then to inturn the marginal portions of the heel breast covering flap, which is split from the sole of the shoe to which the heel is to be attached, into the top or curved portion 10 of 90 the slot along side the inturned marginal portions of the side covers.

The straight portion 12 of the slot may be formed in a machine such as disclosed in the above-mentioned application for United States Letters Patent Serial No. 337,696 and extends heightwise of the breast of the heel along its median portion. In order readily to determine where to terminate the upper part of the straight portion 12 of a slot, that 100

portion is usually formed after forming the curved portion 10 of the slot which, as illustrated in Figs. 4 and 5, extends from one upper breast corner of the heel to the other.

- 5 In order to form in the breast of the heel the curved slot 10 which is curved laterally of itself, the machine is provided with a barrel cutter or saw 14 past which the heel is moved in a predetermined path. The saw 14 is mounted for rotation upon a shaft 16 supported in a bearing 18 of a support 20 and is driven by a pulley 22 secured to the shaft. The support 20 may be adjustably secured to a base plate 24 by bolts 26.
- 10 In order to position the heel and to guide it in a predetermined path past the saw 14, the machine is provided with a carriage or slide 30 having at its under side a T-shaped recess 32 shaped to fit a correspondingly shaped projection 34 of a guide 36 adjustably secured to the base plate 24 by screws 38 in order that the central line of the guide 36 may be conveniently alined in a vertical plane which includes the axis of rotation of the saw 14.
- 15 The slide 30 at its rear end includes a pair of upright bifurcated standards 40 each of which is constructed and arranged to receive a rod 42 secured to a trough-shaped heel holder 44 and having at one end an enlarged head 46 and at the other end a clamp nut 48 which is in threaded relation with the rod 42. The trough-shaped holder 44 fits between the standards 40 and is shaped to engage the outside face of the heel, which face comprises the side and the rear surfaces of the heel as distinguished from the breast of the heel. When the central line of the slide 30 has been adjusted in a vertical plane including the axis of the cutter 14 the bottom ridge 50 of the trough-shaped holder 44 will also lie in that plane. When the heel is placed in the holder 44 with the breast of the heel upwards, as illustrated in Figs. 1 and 2, because of the oval shape of the rim of the attaching face of the heel, the breast of the heel may be centralized so that the median line of the breast of the heel also lies in the above-mentioned vertical plane.
- 20 The heel is positioned lengthwise of the holder 44 by an abutment 42 which engages the top lift receiving face of the heel and against which the heel may be clamped by a pronged fork 54 pivotally secured to an eccentrically mounted lever 56 carried upon a pin 58 which is supported between upstanding ears 60 of the heel holder 44.
- 25 After the heel has been clamped in position in the work holder 44, as above described, the work holder may be set at a predetermined angle relatively to the saw 14, according to the angle at which it is desired to have the slot 10 enter the breast of the heel, by swinging the work holder 44 to its correct position, upon first unloosening the clamp 30 screw 48 and by then tightening up the same.

While making the above angular adjustment the work holder 44 may be raised or lowered in the standards 40 in order that the heel will be in the proper position to cause the slot 10 to extend from one upper breast corner of the heel to the other when the heel has been moved past the saw.

In order rigidly to hold the work holder 44 against the pressure of the saw 14 when the heel, which is supported in position upon the slide 30, is moved past the saw, the slide 30 carries in threaded relation therewith a post 62 having a knurled head which, after the work holder has been angularly adjusted, may be brought into contact with the under side of the work holder 44.

When the heel has been securely positioned in the work holder 44, the slide 30 is moved along the guide 36 to move the heel past the saw 14, the movement toward the saw being limited by contact of a screw 64 adjustably secured to the slide 30 and utilized for limiting the depth of the slot 10 formed in the breast of the heel. Movement of the slide 30 away from the saw 14 is limited by a lug 66 screwed to the base plate 24 and against which the rear portion of the slide 30 engages when it returns to its retracted position.

In order to perform the slotting operation, the heel is positioned in the work holder 44, as illustrated in Figs. 1 and 4, with the breast of the heel upwards and is clamped against the abutment 52 by operating the lever 56. The clamp nut 48 is then unloosened and the work holder 44 is angularly adjusted in order that the slot 10 will enter the breast of the heel at substantially right angles to the breast of the heel. At the same time the heel holder 44 is raised or lowered in the standards 40, in order that the heel may be so positioned that the curved portion 10 of the slot formed in the breast of the heel will extend from one breast corner to the other, this being important since the breast flap, which is tucked into the slot 10, should form a continuation of the rear shank portion of the sole from which the flap is split. After the heel has been adjusted and clamped in position in the heel holder 44, the slide 30 is moved toward the saw 14 until stopped by contact of the screw 64 with the support 20 thereby limiting the depth of the curved portion 10 of the slot formed in the breast of the heel.

Having described my invention, what I claim as new and desire to secure by Letters Patent of the United States is:

1. A machine for operating upon heels having, in combination, a cutter and heel-supporting means constructed and arranged for relative movement to form in the breast of a heel a laterally curved heel cover receiving slot, and guide means constructed and arranged to define the path of relative movement of the cutter and the heel-supporting means.

2. A machine for operating upon heels

having, in combination, a cutter and a support constructed and arranged to engage the curved outside face of a heel to locate the breast of the heel in predetermined relation to the cutter, said cutter and said support being constructed and arranged for relative movement to form in the breast of the heel a laterally curved heel cover receiving slot.

3. A machine for operating upon heels having, in combination, a cutter, a trough-shaped support constructed and arranged to locate a heel with its breast in a position to be slotted, said cutter and said support being mounted for relative movement to form in 15 the breast of the heel a laterally curved heel cover receiving slot.

4. A machine for operating upon heels having, in combination, a rotary cutter, trough-shaped support constructed and arranged to engage the curved outside face of a heel, a carrier upon which the support is mounted, and mechanism constructed and arranged to adjust the support relatively to the carrier in a plane disposed substantially normal to the axis of rotation of the cutter and also constructed and arranged angularly to adjust the support relatively to the cutter, said cutter and said carrier being mounted for relative movement to form in the breast 25 of the heel mounted upon the support a laterally curved heel cover receiving slot.

5. A machine for operating upon heels having, in combination, a cutter, a trough-shaped support to engage the curved outside 35 face of a heel mounted upon the support to centralize and to locate the breast of the heel in a position accessible to be operated upon, and mechanism to position and to clamp the heel heightwise in the support, said cutter and said holder being mounted for relative movement to form a laterally curved heel cover receiving slot in the breast of the heel.

6. A machine for operating upon the heels having, in combination, a cutter, a trough-shaped support to engage the curved outside 45 face of a heel to centralize the heel and to locate the breast thereof in a position accessible to be operated upon, and abutments to engage the top lift receiving and the attaching faces of the heel respectively, to position the heel heightwise thereof in the holder and to clamp the same in place, said cutter and said holder being mounted for relative movement to form a laterally curved heel cover receiving slot in the breast of the heel.

7. A machine for operating upon heels having, in combination, a barrel saw, a holder constructed and arranged to support a heel and shaped to permit free accessibility to the 55 breast of the supported heel, mechanism constructed and arranged angularly to adjust the holder relatively to the saw and also to adjust the holder in a plane perpendicular to the axis of rotation of the saw, said saw and said holder being mounted for movement

relatively to each other to form a curved heel cover receiving slot in the breast of the heel.

8. A machine for operating upon heels having, in combination, a rotary barrel saw, a holder constructed and arranged to support a heel by engagement with the rear portion and the top lift receiving face of the heel, a member constructed and arranged to engage the attaching face of the heel in the holder and to press the top lift receiving face 70 of the heel against the holder, a carrier constructed and arranged to support said holder, and mechanism constructed and arranged angularly to adjust the holder relatively to the carrier and also to adjust the holder in a plane disposed at right angles to the axis of rotation of the saw, said carrier being mounted for movement relatively to the saw to form a curved heel cover receiving slot 75 in the breast of the heel supported in the holder.

9. A machine for operating upon heels having, in combination, a rotary cutter and a slide mounted for movement relatively to each other, a trough-shaped holder mounted 80 upon the slide and constructed and arranged to support a heel and to permit the breast portion of the heel to extend beyond the holder in order to form a heel cover receiving slot in a breast of the heel as the slide and the cutter are moved relatively to each other, and means constructed and arranged angularly to adjust the holder relatively to the slide and to the cutter in order to vary the angle at which the cutter enters the heel, said 85 means also being constructed and arranged to adjust the holder relatively to the slide in a plane disposed at substantially right angles to the path of relative movement of the cutter and the slide in order to locate the position of the slot formed in the breast of the heel.

10. A machine for operating upon heels having, in combination, a rotary saw and a slide mounted for movement relatively to each other, a holder mounted upon the slide and constructed and arranged to support a heel in order to form a heel cover receiving slot in the breast of the heel as the slide and the cutter are moved relatively to each 100 other, and means constructed and arranged angularly to adjust the holder relatively to the slide and to the cutter to vary the angle at which the cutter enters the heel, said means being constructed and arranged to adjust the holder relatively to the slide in a path disposed at an angle to the axis of rotation of the saw.

11. A machine for operating upon heels having, in combination, a rotary barrel saw, 110 a slide mounted for movement axially of the saw, a heel holder constructed and arranged to carry and to position a heel, a member constructed and arranged to secure the heel in said holder, said heel holder being mounted 115

upon the slide and also being constructed and arranged to support the heel in order to form a curved heel cover receiving slot in the breast of the heel as the slide is moved axially of the saw, means constructed and arranged axially to adjust the holder relatively to the slide in order to vary the angle at which the cutter enters the heel, and means constructed and arranged to adjust the holder in a plane disposed at an angle to said axis in order to locate the position of the slot in the breast of the heel.

12. A machine for operating upon heels having, in combination, a rotary barrel saw, a slide mounted for movement axially of the saw, a holder mounted upon the slide and constructed and arranged to support a heel in order to form a heel cover receiving slot in the heel as the heel is moved axially of the saw, means constructed and arranged to adjust the holder angularly with relation to the slide and also to adjust the holder along a rectilinear path relatively to the slide in order to locate the slot formed in the heel as the heel carried by the holder moves past the saw.

13. A machine for operating upon heels having, in combination, a barrel saw and a slide mounted for relative movement in a path extending axially of the saw, and a trough-shaped holder mounted upon the slide and constructed and arranged to support a heel and to centralize the same relatively to said path in order to form in the heel upon relative movement of the holder and the saw a heel cover receiving slot, said holder being constructed and arranged for angular and rectilinear adjustment relatively to the slide in order to vary the angle that the slot forms with the surface of the heel and the position of the slot in the heel, respectively, upon said relative movement of the saw and the slide.

14. A machine for operating upon heels having, in combination, a cutter and a support which are shaped to engage the curved outside face of a heel constructed and arranged for relative movement to form in the breast of the heel a laterally curved heel cover receiving slot, guide means arranged to define the path of relative movement of the cutter and the support at a substantial angle to the breast of the heel positioned on the support, and means constructed and arranged to limit the extent of relative movement of the cutter and the support to control the depth of the slot formed in the heel.

15. A machine for operating upon heels having, in combination, a rotary cutter, a heel receiving support, a carrier upon which the support is mounted, mechanism constructed and arranged to adjust the support relatively to the carrier in a plane disposed substantially normal to the axis of rotation of the cutter and also constructed and arranged angularly to adjust the support rela-

tively to the cutter, said cutter and said carrier being mounted for relative movement to form a heel cover receiving slot in the heel mounted upon the support, and adjustable mechanism constructed and arranged to vary the extent of relative movement of the carrier and the cutter to vary the depth of the slot formed in the heel.

In testimony whereof I have signed my name to this specification.
